BURIAL VAULT

Charles O. A. Brunk, Detroit, Mich., assignor to
Memorial Mausoleum Corporation, Detroit,
Mich., a corporation of Delaware

Application July 30, 1932, Serial No. 627,053

8 Claims. (Cl. 72—7)

This invention relates to burial vaults or mausoleums for individual interment, and has for an important object provision of an individual vault structure adapted to provide increased protection for its contents, and to include means for drying and causing positive circulation of the air within the vault and around the casket, thereby tending to keep remains in better condition than they can be kept by more common methods of burial.

Another important object is the provision of such a vault which need not be buried underground, the cover of which may be left at ground level, but which will nevertheless provide as great protection as, if not greater protection than ordinary underground interment.

Still another object is to provide a burial vault of such character with which a memorial plaque or tablet may be incorporated as a practically monolithic part of the vault itself, and by its permanent attachment thereto provide assurance that the marker or tablet and the contents of the vault will remain permanently associated one with the other.

A still further and important object is the provision of means whereby that portion of the vault to which the tablet is attached, or the tablet itself, or a cover if no tablet is used, may provide positive means for causing circulation of air within the vault.

It is a further object of this invention to provide such a mausoleum in which a casket is housed within interfitting but spaced inner and outer vaults so arranged that positive air circulation, both between the casket and inner vault, and between the outer and inner vaults, will be assured, as well as contact between air so circulating and a portion of the vault itself, or its cover, which is exposed to the air and preferably also to the sunlight aboveground, thereby providing both

a temperature differential which causes air circulation, and means for drying by warming the air contacting this portion during circulation.

Still another object is the provision of improved means for sealing vault covers in place.

A still further object is the provision of a stack construction enabling burying the vault underground if desired, yet providing for such contact between the air in the vault and a portion in communication with the vault which is aboveground as will cause circulation of the air within the vault.

Other objects and advantages will be apparent from the following description wherein reference is made to the accompanying drawings illustrating preferred embodiments of my invention, and

wherein similar reference numerals designate similar parts throughout the several views.

In the drawings:

Figure 1 is a vertical longitudinal section of a vault constructed according to the principles of my invention, showing in dotted lines a casket positioned therein;

Figure 2 is a horizontal section showing the floor of the inner vault in plan, taken substantially on the line 2—2 of Figure 1 and looking in the direction of the arrows;

Figure 3 is a vertical section taken substantially on the line 3—3 of Figure 1 and looking in the direction of the arrows;

Figure 4 is a detail sectional view taken as if on line 4—4 of Figure 1, but showing a somewhat modified cover construction;

Figure 5 is a similar fragmentary detail sectional view showing another modification in which an upwardly extending stack is substituted for the tablet-bearing cover;

Figure 6 is a view partly in side elevation and partly in vertical section of a somewhat modified form of my invention;

Figure 7 is a view similar to Figure 1, of a somewhat modified form of my invention;

Figure 8 is a fragmentary top plan view of the same with the cover partly broken away and the inner slabs removed;

Figure 9 is a vertical section taken substantially on the line 9—9 of Figure 8 and looking in the direction of the arrows;

Figure 10 is a view similar to Figure 8 of another somewhat modified form of my invention; and

Figure 11 is a sectional view thereof analogous to Figure 9, taken substantially on the line 11—11 of Figure 10 and looking in the direction of the arrows.

Referring now to the drawings: Reference character 10 designates an outer vault, the shape of which is clearly shown in the drawings. Both this and the inner vault may if desired be cast of plain or reinforced concrete. The upper edge of the outer vault may be provided with a rabbet or shoulder 11 adapted to receive the complementarily shaped lower edge 12 of the cover 13, which may be sealed in place by means of asphaltum or other suitable cementing means, as 14.

Extending down the inner surfaces of the sides of the vault are a plurality of tapered pilasters 15, adapted, as shown in Figures 1 and 2, to space the inner vault from the sides of the outer, but because of their tapered construction to permit

circulation of air around the inner vault in all directions. Suitable upstanding studs or spacers 16, extending transversely but not entirely across the floor, may be provided to hold the inner vault spaced from the floor of the outer without preventing air circulation beneath the inner vault. An opening 17 is provided in the cover 10, surrounded by an upstanding shoulder or boss 18, over which a smaller cover 19 may be sealed as by means of cement 20. This cover may carry a tablet 21 or other suitable marker, or an inscription may be carved directly in it.

The inner vault may be of similar construction to the outer, although no tapered pilasters similar to those designated 15 are required, it being sufficient to rest the casket 23 upon floor spacers 24, which, in this instance also, best stop short of the sides of the vault to permit free air circulation beneath the casket and around it in all directions. The cover 25 may likewise be sealed in place by means of a rabbeted and cemented joint 26, and an opening 27, also surrounded by an upwardly projecting shoulder 28, may be left therein, and arranged, if desired, directly beneath the opening 17 in the outer cover. These openings are of course to permit air circulating within the vaults to rise into the warmer space immediately beneath the small cover 19, which is ordinarily arranged aboveground.

If desired, as shown in Figure 4, a flat cover, as 19', may be used instead of the cover 19 shown in Figures 1 and 3, and a memorial tablet, as 21', may be arranged upon its horizontal surface, or an inscription carved therein. This is of course entirely optional and frequently depends upon cemetery regulations. If it is desired to cover the mausoleum with earth, it may be buried at greater depth and a stack assembly, formed of hollow cement or vitreous blocks as 29, used to provide communication between the air spaces within the vaults and ground level. The lower block 29 may be cemented over the orifice 17, as by means of the seal 20', in a manner similar to the arrangement of the cover 19, and the upper block as 30 may be formed with an integral top 31 to which the tablet or plaque 21' may be secured.

Figures 7 to 11 inclusive show a somewhat modified construction in which the inner vault is replaced by slab-like supports which nevertheless provide at less expense the same advantages of free air circulation, and strength almost equal to that of the double vault construction previously described. In this form the vault 10³ is provided with side walls somewhat thicker than those of the outer vault previously described, the outer walls are tapered inwardly toward the bottom, as shown in Figure 7, and in place of the pilasters used to space the inner vault and provide for air circulation in the embodiment first described, channels as 15³ are cast in the side and end walls of the vault, which channels extend below the lower casket-supporting slab 22³ and above the upper slab 25³, which serves as an inner cover. The casket rests on the transverse bars or spacers 24³, formed upon the top surface of the lower slab 22³ and extending only partially thereacross. The lower slab 22³ rests upon a shoulder 16³ formed in the wall of the vault near the floor, and a similar shoulder, as 26³, is provided near the top of the vault to support the upper slab 25³. The cover 13 may in its constructional details and the manner in which it is sealed in place be similar to those described in connection with the previously disclosed embodiments, and like

parts have been given like reference characters, distinguished by cube exponents.

In Figures 7, 8 and 9, the ducts or channels 15³ are shown inwardly open throughout their length, thus permitting free circulation of air about both the casket and the space above and below the slabs 22³, 25³. As shown in Figures 10 and 11, however, the inner surfaces of these ducts may be closed except at the top and the bottom, so that the space between the upper and lower slabs constitutes an isolated chamber, which may be either completely sealed, or special provision for circulation therewithin made by means of an orifice such as employed in the covers of the inner vaults first described. In Figures 10 and 15 11 the enclosed ducts are designated 15⁴, and as shown in Figure 11, these ducts are bent inwardly at their lower extremities, as at 15⁵, to open into the space beneath the lower slab 22⁴, and are left open at their upper ends above the upper slab 25⁴.

While it will be apparent that the illustrated embodiments of my invention herein disclosed are well calculated to adequately fulfill the objects and advantages primarily set forth, it is to be understood that the invention is subject to variation, modification and change within the spirit and scope of the subjoined claims.

What I claim is:

1. A burial vault structure comprising a closed receptacle adapted to be placed in the ground and having an upwardly projecting stack portion communicating with the interior of the receptacle but exposable to the air above ground, an inner receptacle within the first mentioned receptacle, means for positioning the inner receptacle within the outer in such manner as to permit air circulation between them and about all sides of the inner receptacle, and means within the inner receptacle to support a casket therein in such manner as to permit circulation of air about all sides thereof.

2. A burial vault structure comprising a closed receptacle adapted to be placed in the ground and having an upwardly projecting portion communicating with the interior of the receptacle but exposable to the air above ground, an inner receptacle within the first mentioned receptacle, means for positioning the inner receptacle within the outer in such manner as to permit air circulation between them and about all sides of the inner receptacle, and means within the inner receptacle to support a casket therein in such manner as to permit circulation of air about all sides thereof, the inner receptacle having an aperture therein providing communication between the inner and outer receptacles, whereby air may circulate between the receptacles and about all sides of both the inner receptacle and the casket.

3. A burial vault structure comprising a closed receptacle adapted to be placed in the ground, an inner receptacle within the outer, means formed integrally with the outer receptacle for positioning the inner receptacle within and in spaced relation to the walls and floors of the outer receptacle to permit free circulation of air about all sides of the inner receptacle, and means within and formed integrally with the inner receptacle for positioning a casket therewithin and spaced from the walls and floor thereof in such manner as to permit free circulation of air about all sides of the casket.

4. A burial vault comprising a hollow receptacle adapted to be buried underground and having a casket chamber therein, and a stack structure

opening into a portion within the receptacle communicating with the casket chamber, and projecting upwardly therefrom and sealed at its top.

5. A burial vault comprising a hollow receptacle adapted to be buried underground and having a casket chamber therein, and a stack structure formed in a plurality of sections, communicating at its lower end with the casket chamber, and projecting upwardly a material distance from the receptacle, said stack being sealed at its top and adapted to be exposed to the air aboveground.

10. In a burial vault structure having a casket chamber therein, a hollow stack connected with the chamber and projecting upwardly from the vault in such manner that the vault may be buried underground with the top of the stack extending upwardly into the air.

15. In a burial vault, an outer receptacle having a floor and an open top, an inner floor therewithin and spaced above the first, a casket supported by

and spaced above the inner floor, an inner cover spaced above the casket, and an outer cover sealed upon the outer receptacle, said outer receptacle having vertically extending air channels each open along the full effective height of its inner side and connecting the space between and the spaces above and below the inner floor and cover.

20. A burial vault structure comprising a closed receptacle adapted to be placed in the ground, an inner receptacle within the outer, spacing and duct-forming members within and extending vertically of the sides of the outer receptacle and defining vertical channels open throughout their height on the inner face of said outer receptacle and tapering inward toward the bottom thereof, and spacing the inner receptacle from the walls of the outer and for providing air channels through which air may circulate about the inner receptacle.
